UNITED STATES PATENT OFFICE

2,434,157

ELECTRONIC PHOTOTIMER

1
Chester S. Heppard, Celina,
Application November 18, 1946, Serial No. 710,460
12 Claims. (Cl. 315--360)

This invention relates to an electronic phototimer. It is an object of this invention to provide an electronic phototimer for photoenlargers and printers, having a selective range of operation whereby the length of exposure may be initially set by an operator and the device will be thereafter controlled accordingly.

2
Figure 2 is a schematic wiring diagram.
Figure 3 is a fragmentary section taken on the line 3--3 of Figure 1.
Figure 4 is a fragmentary detailed section of the platen switch.
Figure 5 is a schematic wiring diagram of a modification of this phototimer.
Figure 6 is a fragmentary section taken on the line 6--6 of Figure 1.

7
fier tube comprising a rectifier section and an amplifier section; a plate circuit across said tube connected to the plate of said amplifier section and cathode of said rectifier section; means connecting a supply circuit to said device, a safe light and an exposure light connected to said switch, said means connecting to the cathodes of said sections, a switch in said supply circuit, means actuated by said plate circuit for operating said switch for selective connection to said safe light or said exposure light, means supplying a charge on the grid of said pentode section for blocking said plate circuit, and means dissipating said charge on said grid, whereby said switch will be connected to the other of said lights.

10. A timing device comprising a rectifier-amplifier tube comprising a rectifier section and an amplifier section; a plate circuit across said tube connected to the plate of said amplifier section and cathode of said rectifier section; means connecting a supply circuit to said device, said supply circuit connecting to the cathodes of said sections, a switch in said supply circuit, a safe light and an exposure light alternately connected through said switch, means actuated by said plate circuit for operating said switch, means establishing a charge on the grid of said pentode section for blocking said plate circuit, and a resistor between said grid and said supply circuit for discharging said grid over a period of time, said switch operating means connecting the switch to the safe light in one position and to the exposure light in another position.

11. An electronic phototimer comprising a switch for selectively connecting a safe light or an exposure light into the circuit of a source of electric supply, a rectifier-amplifier tube having a

rectifier section and a pentode section, a switch operator connected between said rectifier and pentode sections, operating said switch in one direction by current through said sections, a condenser connecting to the grid of said pentode section for supplying an electric charge thereto blocking the current to said operator and actuating said switch in the other direction, and means dissipating said electric charge on said grid re-establishing the current to said operator for returning said operator to its initial position, and means varying the length of time of dissipating the charge on said grid.

12. An electronic phototimer having a switch for connecting an exposure light into an electric supply circuit and an electro-magnetic operator for said switch normally holding said switch in exposure light circuit breaking position, rectifying means connected between one side of said operator and said supply circuit, amplifying means connected between the other side of said operator and said circuit, a condenser connected to said amplifying means for blocking said circuit to said operator, and a resistor connected across said condenser for restoring said circuit after a selected length of time, said switch connecting said exposure light in said supply circuit during the time said condenser blocks the circuit.

CHESTER S. HEPPEARD.
